CONTROL MEANS FOR GARMENT OR
IRONING PRESSESErnest Davis, Syracuse, N. Y., assignor to The
Prosperity Company Inc., Syracuse, N. Y., a
corporation of New YorkApplication February 20, 1931, Serial No. 517,261
Renewed May 1, 1935

31 Claims. (Cl. 121—38)

This invention relates to pressing machines such as garment or laundry ironing presses and particularly to means for controlling the operation of such machines.

5 The principal object of the invention is to provide a novel control mechanism for the power operating means of a pressing machine, which control mechanism will require the operator to use both hands to effect closing of the pressing 10 machine under light pressure, and to use both hands to effect the application of final heavy pressure to the pressing machine.

A further object of the invention is to provide a two-hand control mechanism for controlling the closing of a pressing machine under light pressure, and to provide other two-hand control mechanism for applying final heavy pressure, the heavy pressure control mechanism being inoperative until after the press is closed under light 20 pressure.

25 A further object of the invention is to provide a control mechanism for closing a pressing machine under light pressure, and a control mechanism for applying final heavy pressure, and to provide means between the light pressure and heavy pressure control mechanisms by which the operation of either of the control mechanisms will restore the other control mechanism to inoperative position.

30 A further object of the invention is to provide separate two-hand control means for effecting light and heavy pressure respectively, and to interconnect each manual of one two-hand control mechanism with a manual of the other two-hand control mechanism so that operation of any manual will restore the corresponding manual of the other control mechanism to inoperative position.

35 Other objects and advantages of the invention will appear and will be pointed out as the description proceeds.

The invention consists in the novel features and in the combinations and constructions hereinafter set forth and claimed.

40 In describing this invention reference is had to the accompanying drawings in which like characters designate corresponding parts in all the views.

45 Figure 1 is a fragmentary diagrammatic side elevation of a pressing machine of the type to which the invention is applied.

50 Figure 2 is a schematic showing, mostly in section, of the motor means for operating the press shown in Figure 1, together with the control means therefor in accordance with the invention.

General construction of press.—Figure 1

55 The invention is designed for use with pressing machines having opening and closing movement

such as the pressing machine shown in Figure 1. A pressing head 11 is secured to a yoke 12 pivotally mounted at 13 on a pressing machine frame 14. The yoke 12 is rocked on its pivotal connection 13 to move the pressing head 11 into 5 and out of pressing contact with a buck 15 which is supported by a neck 16 mounted on the pressing machine frame 14. The press is normally held in open position by a spring 17 which is connected at its upper end to the yoke 12 and 10 at its lower end to a leg of the pressing machine frame 14.

A link 20 is pivotally connected to the yoke 12 at 21, and is pivotally connected at 22 with a sleeve 24 which is carried by a link 25. The link 25 is pivotally connected at 28 with the pressing machine frame 14. The link 25 is slidably mounted in a bushing 30 and extends into the sleeve 24. A spring 32 is mounted on the link 25, within the sleeve 24, and presses against the bushing 20 30 and a head 33, of the link 25. The sleeve 24 and link 25 form an extendible link of a toggle of which the link 20 is the other link.

The press is closed under light pressure by a fluid motor 35 of low power which is oscillatively mounted at 37 on the pressing machine frame 14 and has a piston rod 36 pivotally connected at 38 with an extension formed on the link 20. As the press moves into closed position the toggle composed of the link 20, and the sleeve 24 and 30 link 25, moves into straightened position, as shown in Figure 1, so that the lower end of the link 20 moves into a slot 40 formed in the end of a pry-bar 42 which is pivotally mounted at 43 on the pressing machine frame 14. Heavy pressure is applied to the pressing elements by a motor 45 of high power which is oscillatively mounted at 46 on the pressing machine frame, and has a piston rod 47 pivotally connected at 48 with the pry-bar 42. The mechanism thus far 40 described forms no part of the present invention. The low power motor 35 and the high power motor 45 provide motor means which closes the press first with a low power step and then with a 45 high power step.

Operation and control for light pressure

The closing of the press under light pressure is controlled by push buttons 50 and 51. The push button 50 operates the valves in a valve casing 53 50 which contains a normally closed spring-pressed intake valve 54 and a normally open exhaust valve 55. The valves 54 and 55 are connected together by a spacer rod 56 so that they operate as a unit. A valve stem 57 formed on the exhaust 55 valve 55 projects through one end of the valve casing 53. A rocker arm 58 is pivotally mounted at 59 on the valve casing 53. A lever 60, pivotally mounted at 62, transmits motion from the push button 50 to the rocker arm 58 which contacts 60

with the valve stem 57 to operate the valves in the valve casing 53.

A diaphragm chamber 64 is formed on the lower part of the valve casing 53 and contains a diaphragm 65 which operates against a plunger 66. The plunger 66 extends through one end of the diaphragm chamber 64 into contact with one end of the rocker arm 58. When pressure is applied behind the diaphragm 65, in a manner later to be described, the plunger 66 will be moved outwardly against the rocker arm 58 to hold the rocker arm 58 and the valves in the valve casing 53 in operative position.

Working fluid from a fluid supply line 68 is supplied through a pipe 70 to the valve casing 53. When the intake valve 54 is open working fluid from the pipe 70 will pass around the open intake valve 54, through the valve casing 53, and through a pipe 72 which connects with the motor 35. The motor 35 includes a cylinder 74 having a piston 71 therein which is secured to the piston rod 36. A pipe 73 connects the pipe 72 with a valve casing 75.

The valve casing 75 contains an exhaust valve 76 formed with a valve stem 77 which projects through one end of the valve casing into contact with a rocker arm 79 which is pivotally mounted at 80 on the front of the valve casing 75.

A diaphragm chamber 82 is formed on the lower part of the valve casing 75 and contains a diaphragm 84 which operates against a plunger 86. The plunger 86 extends through the end of the diaphragm chamber 82 into contact with one end of the rocker arm 79. When working fluid under pressure is supplied to the diaphragm chamber 82, behind the diaphragm 84, the plunger 86 will be moved outwardly against the rocker arm 79 and will hold the rocker arm 79 and the exhaust valve 76 in operated position. Motion of the push button 51 is transmitted through a lever 88, which is pivotally mounted at 89, to the rocker arm 79 which operates against the valve stem 77 to move the exhaust valve 76 into closed position.

Operation of the push button 50 will open the supply or intake valve 54 and close the exhaust valve 76 so that working fluid from the fluid supply line 68 may flow through the pipe 70, around the open intake valve 54, through the valve casing 53, and pipe 72, to the cylinder 74 of the motor 35. If the push button 51 has not been operated however, the exhaust valve 76 will be open and working fluid from the pipe 72 will escape through the pipe 73, valve casing 75, and past the open exhaust valve 76, so that pressure in the pipe 72 will not build up enough to move the piston 71. If the push button 51 is operated to close the exhaust valve 76 pressure in the pipe 72 will build up and this working fluid under pressure will operate the piston 71 to move the piston rod 36 upwardly and close the press under light pressure.

A port opening 90 is formed in the wall of the cylinder 74 in such a position that it will be uncovered by the piston 71 at substantially the same time that the pressing jaws come in contact. The port opening 90 communicates with a chamber 92 which is connected by a pipe 94, and a branch pipe 96, with a valve casing 97 which contains a spring-loaded check valve 98. A pipe 99 connects the other end of the valve casing 97 to a pipe 100, which leads to the diaphragm chamber 82, and to a pipe 101, which leads to the diaphragm chamber 64.

When the push buttons 50 and 51 are oper-

ated to supply working fluid to the motor 35, as previously described, the piston 71 will move upwardly in the cylinder 74 and will uncover the port 90. When the port 90 is thus uncovered working fluid from the cylinder 74 will flow through the port opening 90, chamber 92, pipes 94 and 96, past the check valve 98, through the valve casing 97, pipe 99, and through the pipes 100 and 101 to the diaphragm chambers 82 and 64 respectively. When working fluid is thus supplied to the diaphragm chambers 82 and 64 the diaphragms therein will be operated to move the plungers 86 and 66 respectively into position to hold their respective valves in operated position. When the valves are thus locked in operated position by the pressure in the diaphragm chambers it is no longer necessary for the operator to hold the push buttons 50 and 51 depressed.

When the push button 50 is released a spring 104 returns the bell crank 60 and push button 50 to normal position. When the push button 51 is released a spring 105 returns the bell crank 88 and push button 51 to normal position.

Operation and control for heavy pressure

25

The high power fluid motor 45 is operated, as previously described, to apply final heavy pressure to the pressing jaws. The fluid motor 45 includes a cylinder 108 containing a piston 109 which is rigidly secured to the piston rod 47.

Working fluid is supplied to the cylinder 108 through a pipe 110 which connects with a valve casing 112.

The valve casing 112 contains a normally closed intake valve 114 and a normally open exhaust valve 116 which are connected together by a spacer rod 118 so that they operate as a unit. A spring 120 holds the valves 114 and 116 in normal position and a rocker arm 122 operates against a stem of the exhaust valve 116 to close the exhaust valve 116 and open the intake valve 114.

The rocker arm 122 is operated by a plunger 124 which extends through one end of a diaphragm chamber 126 and is operated by a diaphragm 128 when working fluid is supplied to the diaphragm chamber 126 behind the diaphragm 128.

The diaphragm chamber 126 is connected by a pipe 130 and a pipe 132 with a valve casing 134.

The valve casing 134 contains a normally closed intake valve 136 and a normally open exhaust valve 138 which are identical in construction with the valves 114 and 116 in the valve casing 112. These valves 136 and 138 are operated by a 55 rocker arm 140. The rocker arm 140 is operated by a manual control lever 142, and when the intake valve 136 is opened and working fluid enters the valve casing 134 it will flow through a duct 144 to a diaphragm chamber 146 and actuate a 60 diaphragm 147 which moves a plunger 148 upwardly against one end of the rocker arm 140 to hold the rocker arm 140 in operated position.

The manual control lever 142 is provided with a handle portion located adjacent the push button 50 in such position that the operator may actuate this manual control lever 142 with one finger while another finger is in position on the push button 50. The manual control lever 142 is connected by a link 150 with the lever 60 so that operation of the push button 50 and lever 60 to open the intake valve in the valve casing 53 will cause the manual control lever 142 to move into inoperative position. When the manual control lever is moved to open the intake valve 75

136 in the valve casing 134 the link 150 will cause the lever 60 and push button 50 to move into inoperative position.

In order to provide two-hand control of the high pressure operating means a pipe 154 is connected with the pipe 132 and with a valve casing 155 which contains an exhaust valve 156. The exhaust valve 156 may be closed by a manual control lever 158 which operates against a rocker arm 160 which contacts with a stem of the exhaust valve 156. Operation of the manual control lever 142 to supply working fluid to the pipe 132, and pipe 130, to operate the valves in the valve casing 112 cannot build up sufficient pressure to operate these valves in the valve casing 112 as long as working fluid can escape through the pipe 154 and past the open exhaust valve 156. In order to effectively supply working fluid to the diaphragm chamber 126 to operate the valves in the valve casing 112 it is necessary therefore that the operator actuate both of the manual control levers 142 and 158.

The manual control lever 158 is connected by a link 164 with the lever 88 in the same manner as previously described in connection with the link 150. This interconnection of the manual control levers 142 and 158 with the push buttons 50 and 51 respectively makes it impossible to operate the press with one control member stuck or tied in operated position so that the two-hand control safety feature is lost.

Referring to Figure 1 it will be obvious that it is desirable to provide means to prevent the operation of the motor 45 and pry-bar 42 before the press has reached substantially closed position with the lower end of the link 20 in position over the slot 40. The means to prevent operation of the motor 45 before the press is closed are shown in Figure 2. Operation of the motor 45 is controlled by the intake valve 114 in the valve casing 112. This intake valve 114 is normally closed and can be opened only by supplying working fluid under pressure through the pipes 132 and 130 to the diaphragm chamber 126. The supply of working fluid to the pipe 132 is controlled by the intake valve 136. This intake valve 136 may be opened at any time but the only supply of working fluid to the valve casing 134 and intake valve 136 is through the pipe 94 and no working fluid will be supplied through this pipe until the piston 71 has uncovered the port 90. As previously described the port 90 is so located that it will not be uncovered by the piston 71 until the pressing jaws are substantially in contact.

Release of high or low pressure

When the press is closed under heavy pressure such pressure may be released and the press held closed under light pressure. Heavy pressure is thus released by operating a release handle 166 which opens a normally closed release valve 168 and permits working fluid to escape from the pipe 132 and pipe 130. When the release valve 168 is thus opened working fluid in the diaphragm chamber 126 will exhaust through the pipe 130, pipe 132, and around the open release valve 168. At the same time working fluid in the diaphragm chamber 146 will exhaust through the duct 144, valve casing 134, and pipe 132, faster than working fluid enters the valve casing 134 around the open intake valve 136.

This escape of working fluid from the diaphragm chambers 126 and 146 will permit the intake valves 114 and 136 respectively to return to

normal closed position thus cutting off the supply of working fluid to the motor 45 and diaphragm chamber 126 respectively. When the intake valve 114 is thus permitted to return to normal closed position the exhaust valve 116 will return to open position and working fluid from the fluid motor 45 will exhaust through the pipe 110, valve casing 112, and past the open exhaust valve 116.

A release valve 170 is located in a valve casing 172 which is connected by a pipe 174 with the pipe 101. The release valve 170 may be operated by the same release lever 166 which operates the release valve 168 but the stem of the release valve 170 is preferably made shorter than the stem of the release valve 168 so that additional movement of the release lever 166 is necessary in order to open the release valve 170. When the release valve 170 is open working fluid will escape from the diaphragm chambers 82 and 64 through the pipes 100, 101 and 174, faster than working fluid enters the pipes 100 and 101 through the check valve casing 97, and the reduced pressure in the diaphragm chambers 82 and 64 will permit the exhaust valve 76 to open and the intake valve 54 to close. When the intake valve 54 closes the exhaust valve 55 will open and working fluid from the motor 35 will exhaust through the pipes 72 and 73 past the open exhaust valves 55 and 76 respectively. When the working fluid is thus free to escape from the fluid motor 35 the spring 17 (see Figure 1) will return the press to open position.

From the above description it will be apparent that the invention provides a novel four-finger control in which the operator controls the closing of the press under light pressure by two-hand control means, and controls the closing of the press under heavy pressure by other two-hand control means which are interconnected with the light pressure two-hand control means so that the press cannot be operated if one of the manual controls of either of the two-hand control means is stuck or tied in operated position. The invention is illustrated in its preferred embodiment but changes and modifications may be made without departing from the spirit of the invention as set forth in the appended claims.

What I claim is:

1. In a garment or laundry pressing machine, in combination, cooperative pressing jaws one of which is movable with respect to the other; operating mechanism for the movable pressing jaw including, a fluid motor to bring the pressing jaws together under light pressure, and a fluid motor to apply heavy pressure to the pressing jaws; valve means to control the flow of working fluid to the light pressure motor; valve means rendered operative upon closing of the press to control the flow of working fluid to the heavy pressure motor; two-hand control means for the valve means for the light pressure motor; and two-hand control means for the valve means for the heavy pressure motor.

2. In a garment or laundry pressing machine, in combination, cooperative pressing jaws one of which is movable with respect to the other; operating mechanism for the movable pressing jaw including, a first motor means to bring the pressing jaws together under light pressure; a second motor means, including a cylinder and piston motor to apply heavy pressure to the pressing jaws; valve means, and two-hand control mechanism therefor to supply working fluid to the first motor means; valve means to control the supply of motive fluid to the second motor means; a

- conduit to supply working fluid to the second valve means; a port in the wall of the cylinder of the first motor means for admitting working fluid from said cylinder to the conduit, said port being located in position to be uncovered by the piston when the pressing jaws are substantially in contact under light pressure.
3. In a garment or laundry pressing machine, in combination, cooperative pressing jaws one of which is movable with respect to the other; operating mechanism for the movable pressing jaw including, a fluid motor for bringing the pressing jaws together under light pressure, and a fluid motor for applying heavy pressure to the pressing jaws; means to control the supply of working fluid to the light pressure fluid motor; means to control the supply of working fluid to the heavy pressure fluid motor; two-hand means to operate each of the working fluid supply control means; and means between said two-hand means by which the operation of one of said two-hand means restores the other to inoperative position.
4. In a garment or laundry pressing machine, in combination, cooperative pressing jaws one of which is movable with respect to the other; operating mechanism for the movable pressing jaw including, a fluid motor for bringing the pressing jaws together under light pressure, and a fluid motor for applying heavy pressure to the pressing jaws; valve means to control the supply of working fluid to the motor which effects light pressure; valve means to control the supply of working fluid to the motor which effects heavy pressure; a separate two-hand mechanism associated with each of said valve means for operating the same to supply working fluid to the respective motors; and means connecting the operator operated mechanisms for transmitting movement of one to the other so that movement of either of said operator operated mechanisms into operative position moves the other into inoperative position.
5. In a garment or laundry pressing machine, in combination, cooperative pressing jaws one of which is movable with respect to the other; operating mechanism for the movable pressing jaw including, a fluid motor for bringing the pressing jaws together under light pressure; and a fluid motor for applying heavy pressure to the pressing jaws; means to control the supply of working fluid to the light pressure fluid motor; means to control the supply of working fluid to the heavy pressure fluid motor; two-hand control means including a pair of manuals for operating each of the working fluid supply control means; and means operated by one of the manuals when moved into operative position for restoring one of the manuals of the other control means to inoperative position.
6. In a garment or laundry pressing machine in combination cooperative pressing jaws one of which is movable with respect to the other; operating mechanism for the movable pressing jaw including a fluid motor for bringing the pressing jaws together under light pressure, and a fluid motor for applying heavy pressure to the pressing jaws; valve means to control the supply of working fluid to the motor which effects light pressure; valve means to control the supply of working fluid to the motor which effects heavy pressure; two-hand control means including a pair of manuals associated with each of said valve means for operating the same to supply working fluid to the respective motors; and means for transmitting movement of a manual, of one of

the two-hand control means, to a manual of the other two-hand control means so that movement of either manual into operative position moves the other into inoperative position.

7. In a garment or laundry pressing machine, in combination, cooperative pressing jaws one of which is movable with respect to the other; operating mechanism for the movable pressing jaw including, a fluid motor for bringing the pressing jaws together under light pressure, and a fluid motor for applying heavy pressure to the pressing jaws; valve means to control the supply of working fluid to the motor which effects light pressure; valve means to control the supply of working fluid to the motor which effects heavy pressure; two-hand control means including a pair of manuals associated with each of said valve means for operating the same to supply working fluid to the respective motors; and means between each of the manuals of one of the two-hand control means and the corresponding manual of the other two-hand control means for transmitting movement of any one of the manuals to the corresponding manual of the other two-hand control mechanism so that movement of any manual into operative position shifts the corresponding manual of the other two-hand control mechanism into inoperative position.

8. A garment or ironing press comprising, coacting press jaws, a low power motor to close the press jaws under light pressure, a feed line including, two-hand control members connected to the motor to energize same, means cooperating with the two-hand control members to compel an operator to keep his hands on both of the two-hand controls until the press closes, a high power motor operatively connected with a press jaw to produce heavy jaw pressure after the press is closed by the low power motor, a feed line including two-hand control members connected with the high power motor, and an operating connection between one control member of each two-hand control, whereby movement of one set of two-hand controls to energize one motor positively resets the other two-hand control members to ineffective position so the latter is not in position to energize the other motor.

9. A press having coacting press jaws and motor means therefor, a feed line having a valve means including, a closed intake valve connected with the motor means, a two-hand control having a pair of levers movable in one direction to operate the valve means, a second feed line having a second closed valve means including a closed intake valve connected with the motor means, a second two-hand control also having a pair of levers movable in one direction to operate the second valve means, and a link connection between one lever of each pair, whereby movement of one lever of one two-hand control in one direction returns the lever of the other pair to inoperative position.

10. A garment or ironing press comprising, in combination, cooperating pressing jaws, operating mechanism therefor including, a low power motor, and a high power motor; control mechanism including a first control means for the low power motor, a second control means for the high power motor, a manual for operating the first control means to actuate the low power motor and close the press under light pressure, means to hold the first control means in operated position, a manual for operating the second control means to actuate the high power motor and close the press under heavy pressure, and interconnect-

ing means between the manuals whereby the actuation of one manual returns the other to inoperative position.

11. A garment or ironing press comprising, in combination, cooperating press jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, a valve connected with the high power motor and controlling its operation, a manual for operating the valve connected with the high power motor and closing the press under heavy pressure, and interconnecting means between the manual for the high power motor and one of the spaced manuals whereby the actuation of one manual returns the other to inoperative position.

12. A garment or ironing press comprising, in combination, cooperating press jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, a second closed intake valve, said second intake valve being connected with the high power motor, a manual for opening said second intake valve and closing the press under heavy pressure, and interconnecting means between the second intake valve manual and one of the spaced manuals whereby the actuation of one manual returns the other to inoperative position.

13. A garment or ironing press comprising, in combination, cooperating pressing jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, a second closed intake valve, said second intake valve being connected with the high power motor, a manual for opening said second intake valve and closing the press under heavy pressure, means to hold said second intake valve in operated position, and interconnecting means between the second intake valve manual and one of the spaced manuals whereby the actuation of one manual returns the other to inoperative position.

14. A garment or ironing press comprising, in combination, cooperating pressing jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, means to hold the valves in operated position, a second closed intake valve, said second valve being connected with the high power motor, a manual for opening said second intake valve and closing the press under heavy pressure, means to hold said second intake valve in operated

position, and interconnecting means between the second intake valve manual and one of the spaced manuals whereby the actuation of one manual returns the other to inoperative position.

15. A garment or ironing press comprising, in combination, cooperating press jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, a second open exhaust valve, said valve being connected with the high power motor, a manual for closing said second exhaust valve so that the press closes under heavy pressure, means connecting the high power motor with a source of power upon a predetermined extent of movement of the operating mechanism, and interconnecting means between the manual for the second exhaust valve and one of the spaced manuals whereby the actuation of one manual returns the other to inoperative position.

16. A garment or ironing press comprising, in combination, cooperating pressing jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, a second open exhaust valve, said exhaust valve being connected with the high power motor, a manual for closing said second exhaust valve so that the press closes under heavy pressure, means connecting the high power motor with a source of power upon a predetermined extent of movement of the operating mechanism, and interconnecting means between the manual for the second exhaust valve and the manual for the exhaust valve for the low power motor whereby the actuation of one manual returns the other to inoperative position.

17. A garment or ironing press comprising, in combination, cooperating pressing jaws; operating mechanism therefor including, a low power motor, and a high power motor; control means for the operating mechanism including a closed intake valve and an open exhaust valve connected with the low power motor, a manual for each valve to actuate the valves and close the press under light pressure, the manuals being spaced apart so as to require the use of two hands, means to hold the valves in operated position, a second open exhaust valve, said second exhaust valve being connected with the high power motor, a manual for closing said second exhaust valve so that the press closes under heavy pressure, means connecting the high power motor with a source of power upon a predetermined extent of movement of the operating mechanism, and interconnecting means between the manual for the second exhaust valve and one of the spaced manuals whereby the actuation of one manual returns the other to inoperative position.

18. A garment or ironing press comprising, in combination, cooperating press jaws; operating mechanism therefor including, a low power motor, and a high power motor; control means for the operating mechanism including a closed in-

take valve and an open exhaust valve connected with the low power motor, a manual for each valve to actuate the valves and close the press under light pressure, the manuals being spaced apart so as to require the use of two hands, means 5 to hold the valves in operated position, a second open exhaust valve, said second exhaust valve being connected with the high power motor, a manual for closing said second exhaust valve so that the press closes under heavy pressure, means holding the second exhaust valve closed, means connecting the high power motor with a source of power upon a predetermined extent of movement of the operating mechanism, and interconnecting means between the manual for the second exhaust valve and one of the spaced manuals whereby the actuation of one manual returns the other to inoperative position.

19. A garment or ironing press comprising, cooperative pressing jaws one of which is movable with respect to the other; operating mechanism for the movable pressing jaw including, a fluid motor to bring the pressing jaws together under light pressure, and a fluid motor to apply heavy pressure to the pressing jaws; valve means to control the flow of working fluid to the light pressure motor; valve means controlling the flow of working fluid to the heavy pressure motor; means operated upon a predetermined extent of movement of the operating mechanism to connect the working fluid to the valve means for the heavy pressure motor; two-hand control means for the valve means for the light pressure motor; and two-hand control means for the valve means for the heavy pressure motor.

20. A garment or ironing press comprising, in combination, cooperating pressing jaws one of which is movable with respect to the other; operating mechanism for the movable pressing jaw including a fluid motor for closing the press under light pressure, and a fluid motor for closing the press under heavy pressure; valve means to control the supply of working fluid to the light pressure motor including, a normally closed intake valve, and a normally open exhaust valve; valve means to control the supply of working fluid to the heavy pressure motor including, a normally closed intake valve, and a normally open exhaust valve; a pair of manuals associated with each of said valve means for operating the same to supply working fluid to the respective motors; and means between each of one pair of manuals and one of the manuals of the other pair for transmitting movement of any one of the manuals to the corresponding manual of the other pair of manuals so that movement of any manual into operative position shifts the corresponding manual of the other pair of manuals into inoperative position.

21. A garment or ironing press comprising, in combination, cooperating pressing jaws one of which is movable with respect to the other; operating mechanism for the movable pressing jaw including a fluid motor for closing the press under light pressure, and a fluid motor for closing the press under heavy pressure; valve means to control the supply of working fluid to the light pressure motor including, a normally closed intake valve, a normally open exhaust valve, and means operable upon a predetermined extent of movement of the operating mechanism to hold the intake valve open and the exhaust valve closed; valve means to control the supply of working fluid to the heavy pressure motor including, a normally closed intake valve, and a normally open

exhaust valve; two-hand control means including a pair of manuals associated with each of said valve means for operating the same to supply working fluid to the respective motors; and means between each of the manuals of one of the two-hand control means and the corresponding manual of the other two-hand control means for transmitting movement of any one of the manuals to the corresponding manual of the other two-hand control means so that movement of any manual into operative position shifts the corresponding manual of the other two-hand control means into inoperative position.

22. A garment or ironing press comprising, in combination, cooperating pressing jaws one of which is movable with respect to the other; operating mechanism for the movable pressing jaw including a fluid motor for closing the press under light pressure, and a fluid motor for closing the press under heavy pressure; valve means to control the supply of working fluid to the light pressure motor including, a normally closed intake valve, a normally open exhaust valve, and means operable upon a predetermined extent of movement of the operating mechanism to hold the intake valve open and the exhaust valve closed; valve means to control the supply of working fluid to the heavy pressure motor including, a normally closed intake valve, a normally open exhaust valve, and means operable upon actuation of the valve means to hold the exhaust valve closed and the intake valve open; two-hand control means including a pair of manuals associated with each of said valve means for operating the same to supply working fluid to the respective motors; and means between each of the manuals of one of the two-hand control means and the corresponding manual of the other two-hand control means for transmitting movement of any one of the manuals to the corresponding manual of the other two-hand control means so that movement of any manual into operative position shifts the corresponding manual of the other two-hand control means into inoperative position.

23. A garment or ironing press comprising, in combination, cooperating pressing jaws one of which is movable with respect to the other; operating mechanism for the movable press jaw including a fluid motor for closing the press under light pressure, and a fluid motor for closing the press under heavy pressure; a first valve means to control the supply of working fluid to the light pressure motor including, a normally closed intake valve, a normally open exhaust valve, and pressure holding means to hold the intake valve open and the exhaust valve closed; a second valve means to control the supply of working fluid to the heavy pressure motor including, a normally closed intake valve, and a normally open exhaust valve; and two-hand control means including a pair of manuals associated with each of said valve means for operating the same to supply working fluid to the respective motors.

24. A garment or ironing press comprising, in combination, cooperating pressing jaws one of which is movable with respect to the other; operating mechanism for the movable pressing jaw including a fluid motor for closing the press under light pressure, and a fluid motor for closing the press under heavy pressure; a first valve means to control the supply of working fluid to the light pressure motor including, a normally closed intake valve, a normally open exhaust valve, and pressure holding means to hold the

intake valve open and the exhaust valve closed; a second valve means to control the supply of working fluid to the heavy pressure motor including, a normally closed intake valve, and a normally open exhaust valve; means operable upon a predetermined extent of movement of the operating mechanism to connect fluid pressure to the pressure holding means and the second valve means; two-hand control means including a pair of manuals associated with each of said valve means for operating the same to supply working fluid to the respective motors; and means between each of the manuals of one of the two-hand control means and the corresponding manual of the other two-hand control means for transmitting movement of any one of the manuals to the corresponding manual of the other two-hand control means so that movement of any manual into operative position shifts the corresponding manual of the other two-hand control means into inoperative position.

25. In a garment or laundry pressing machine, in combination, cooperative pressing jaws one of which is movable with respect to the other; operating mechanism for the movable pressing jaw including, a fluid motor for bringing the pressing jaws together under light pressure, and a fluid motor for applying heavy pressure to the pressing jaws; means to control the supply of working fluid to the fluid motors; one of said control means including an intake valve and an exhaust valve operable independently of the intake valve; operator actuated means to operate the intake valve and the exhaust valve thereby forming two-hand means; operator actuated means to operate the other control means; and means between said two-hand means and the operator actuated means by which the operation of said latter means restores the operator actuated means for the exhaust valve to inoperative position.

26. In a garment or laundry pressing machine, in combination, cooperative pressing jaws one of which is movable with respect to the other; operating mechanism for the movable pressing jaw including, a fluid motor for bringing the pressing jaws together under light pressure, and a fluid motor for applying heavy pressure to the pressing jaws; means to control the supply of working fluid to the fluid motors, each of said control means including an intake valve and an exhaust valve; operator actuated means to operate each of the working fluid valves thereby forming two-hand means; and means between said operator actuated means for the exhaust valves by which the operation of one of said operator actuated means restores the other to inoperative position.

27. A garment or ironing press comprising, in combination, cooperating pressing jaws, operating mechanism therefor including, a low power motor, and a high power motor; control mechanism including a first control means for the low power motor, a second control means for the high power motor, a manual for operating the first control means to actuate the low power motor and close the press under light pressure, a manual for operating the second control means to actuate the high power motor and close the press under heavy pressure, and interconnecting means between the manuals whereby the actuation of the manual for the high power motor returns the manual for the low power motor to inoperative position.

28. A garment or ironing press comprising, in combination, cooperating pressing jaws, operat-

ing mechanism therefor including, a low power motor, and a high power motor; control mechanism including a first control means for the low power motor, a second control means for the high power motor, a manual for operating the first control means to actuate the low power motor and close the press under light pressure, a manual for operating the second control means to actuate the high power motor and close the press under heavy pressure, and interconnecting means between the manuals whereby the actuation of one manual returns the other to inoperative position.

29. A garment or ironing press comprising, in combination, cooperating pressing jaws, operating mechanism therefor including, a low power motor, and a high power motor; control mechanism including a first control means for the low power motor, a second control means for the high power motor, a manual for operating the first control means to actuate the low power motor and close the press under light pressure, a manual for operating the second control means to actuate the high power motor and close the press under heavy pressure, interconnecting means between the manuals whereby the actuation of the manual for the high power motor returns the manual for the low power motor to inoperative position, and means to hold the press in closed position.

30. A garment or ironing press comprising, in combination, cooperating pressing jaws, operating mechanism therefor including motor means for applying low power and high power pressure between the pressing jaws; control mechanism including a first control means for the low power step, a second control means for the high power step, a manual for operating the first control means to actuate the low power step to close the press under light pressure, fluid pressure means to hold the first control means in operated position, means operable upon a predetermined extent of movement of the operating mechanism to connect the fluid pressure holding means and the second control means with a source of fluid pressure, a check valve between the aforesaid means and the fluid pressure holding means, and a manual for operating the second control means to actuate the high power step and close the press under heavy pressure.

31. A garment or ironing press comprising, in combination, cooperating pressing jaws, operating mechanism therefor including motor means for applying low power and high power pressure between the pressing jaws; control mechanism including a first control means for the low power step, a second control means for the high power step, a manual for operating the first control means to actuate the low power step to close the press under light pressure, fluid pressure means to hold the first control means in operated position, means operable upon a predetermined extent of movement of the operating mechanism to connect the fluid pressure holding means and the second control means with a source of fluid pressure, a check valve between the aforesaid means and the fluid pressure holding means, a manual for operating the second control means to actuate the high power step and close the press under heavy pressure, and interconnecting means between the manuals whereby the actuation of one manual returns the other to inoperative position.
